UNITED STATES PATENT OFFICE

169,819

TABLE

Earl R. Kupferer, St. Louis, Mo.

Application March 25, 1953, Serial No. 24,193

Term of patent 14 years

(Cl. D33—14)

To all whom it may concern:

Be it known that I, Earl R. Kupferer, a citizen of the United States, residing at the city of St. Louis, State of Missouri, have invented a new, original, and ornamental Design for a Table, of which the following is a specification, reference being had to the accompanying drawing, forming a part hereof.

Fig. 1 is a side elevational view of a table embodying my new design;

Fig. 2 is an end elevational view;

Fig. 3 is a perspective view; and

Fig. 4 is a top plan view.

I claim:

The ornamental design for a table, as shown.

EARL R. KUPFERER.
